Inventor
George Mc Graham,
by Robert Burns
Attorney.

UNITED STATES PATENT OFFICE.

GEORGE M. GRAHAM, OF CHICAGO, ILLINOIS, ASSIGNOR, BY MESNE ASSIGNMENTS, TO SUSPENSION STEEL CONCRETE COMPANY, A CORPORATION OF DELAWARE.

REINFORCING-FRAME FOR CONCRETE STRUCTURES.

974,657.

Specification of Letters Patent.

Patented Nov. 1, 1910.

Application filed April 21, 1909. Serial No. 491,346.

To all whom it may concern:

Be it known that I, GEORGE M. GRAHAM, a citizen of the United States of America, and a resident of Chicago, in the county of 5 Cook and State of Illinois, have invented certain new and useful Improvements in Reinforcing-Frames for Concrete Structures, of which the following is a specification.

This invention relates to reinforced concrete structures of the type described in detail in my prior Letters Patent No. 865,490, dated September 10, 1907, and No. 888,999, dated May 26, 1908, and has for its object to provide a simple and economical structural arrangement and combination of parts in a skeleton reinforcing floor frame, by which the method of forming concrete floors set forth in my companion application Serial No. 491,347, filed April 21, 1909, can be 10 carried on in a practical and economical manner; all as will hereinafter more fully appear.

In the accompanying drawings:—Figure 1, is a plan view of a skeleton floor structure showing the present improvement as applied to a twelve unit floor frame, the wire center being shown in a partially applied condition. Fig. 2, is a longitudinal section on line $x-x$ Fig. 1, illustrating the 15 wire or rod windings forming the upper and lower skeleton centers without any tie or connecting links. Fig. 3, is a similar view with the connecting links applied. Fig. 4, is a detail elevation of one of the connecting links

Similar numerals of reference indicate like parts in the different views.

Referring to the drawings, 1 represents the vertical posts; 2 the horizontal round beams, and 3 the coupling members by which the beams are secured together and to the posts to constitute the supporting frame for the skeleton web or center herein-after described. Said supporting frame 20 comprises a multiplicity of units or panels of a uniform size and varying in number in accordance with the horizontal area of the structure, and to this end will in addition to the round border beams 2 above described, be provided with a series of intermediate round beams 4, arranged in right angle relation as shown.

5 are windings of wires arranged in crossed relation to constitute upper and 25 lower wire skeleton centers as set forth in

detail in my former Patent No. 865,490, of September 10, 1907. In the present improvement said wire windings are continuous the entire length as well as width of the floor frame, in order to encompass the entire series of floor units above referred to. Such windings are made under ordinary tension, and the strands comprising the lower web of the skeleton center formed by 60 said windings will have an initial natural sag which is taken up and in turn assumed by the strands comprising the upper web of the skeleton center, when the concrete mass is applied thereto to form the floor proper as set forth in detail in my companion application Serial No. 491,347, filed April 21, 1909.

With exceedingly long or wide structures, too much sag in the lower web or center is neutralized by a series of tie or connecting 65 links 6, extending between the strands of the upper and lower skeleton centers, and arranged immediately adjacent to the beams 2 and 4, as shown, and with a view to uniformity it is preferable to arrange said 70 links adjacent to all of said beams, so as to form a series of sub-sags in the lower skeleton center as illustrated in Fig. 3, and provide as well intermediate supports therefor 75 to hold the mass of concrete from which the ceiling is formed.

Having thus fully described my said invention what I claim as new and desire to secure by Letters Patent, is:—

1. A reinforcing frame for the floors of 90 concrete structures, comprising a series of posts, a series of round border beams, a series of intermediate beams, couplings connecting said beams and posts together into a series of units, and a continuous winding 95 of wire encompassing said frame and forming a skeleton center therefor, substantially as set forth.

2. A reinforcing frame for the floor of 100 concrete structures, comprising a series of posts, a series of round border beams, a series of intermediate beams, couplings connecting said beams and posts together into a series of units, and a continuous winding 105 of wire in crossed relation and encompassing said frame to form a skeleton center therefor, substantially as set forth.

3. A reinforcing frame for the floors of 110 concrete structures, comprising a series of posts, a series of round border beams, a se-

ries of intermediate beams, couplings connecting said beams and posts together into a series of units, a continuous winding of wire encompassing said frame and forming a skeleton center therefor, and a series of tie links connecting the upper and lower strands of said winding together, substantially as set forth.

4. A reinforcing frame for the floors of concrete structures, comprising a series of posts, a series of round border beams, a series of intermediate beams, couplings connecting said beams and posts together into

a series of units, a continuous winding of wire in crossed relation and encompassing said frame to form a skeleton center therefor, and a series of tie links connecting the upper and lower strands of said winding together, substantially as set forth.

Signed at Chicago, Illinois, this 12th day 20 of April 1909.

GEORGE M. GRAHAM.

Witnesses:

ROBERT BURNS,
L. HOLDEN.
